APPARATUS FOR SEALING OFF THE STRATA
IN A WELL BORE

Arthur L. Armentrout, Bakersfield, and Elwin B. Hall, Los Angeles, Calif., assignors, by mesne assignments, to Security Engineering Co., Inc., Whittier, Calif., a corporation of California

Application July 5, 1935, Serial No. 29,989

5 Claims. (Cl. 166—1)

This invention relates to a method and apparatus for excluding encroaching fluids from a well. A general object of this invention is to provide a rapid, practical and inexpensive method for sealing or shutting off water or other undesirable fluids from a well and to provide a simple, practical and effective apparatus for carrying out said method.

In the drilling of deep wells such as oil wells and gas wells, the bore often penetrates strata bearing water and/or water with a small portion of oil and/or gas. It is usually necessary to exclude these undesired encroaching fluids from the well. For example, where a water sand or a stratum bearing water is located either above or below a productive oil or gas stratum in relatively close proximity thereto, it is desirable to exclude or seal off the water from the well without sealing off the productive stratum or strata. Heretofore much difficulty has been encountered in excluding or sealing off encroaching fluids from wells.

An object of this invention is to provide a simple method by means of which encroaching fluid from a stratum of formation in a well may be effectively and fully excluded or sealed off.

Another object of this invention is to provide a method for excluding encroaching fluids from a well without obstructing the well for the subsequent passage of tools, the setting of casing or a liner or other subsequent operations. Upon the completion of the method of the present invention the water or encroaching fluid is fully and dependably sealed from the well and the well bore at that point is clear and unobstructed, being of the same diameter as the adjacent portions of the bore.

Another object of this invention is to provide a method for excluding fluids from a well that does not necessitate the setting of metal casing, metal liners or other metal parts likely to interfere with or obstruct subsequent operations.

Another object of this invention is to provide a method for sealing water and the like from deep wells that may be employed to seal off the encroaching fluid at any point in the open well bore as required, and that may be employed to seal leaking casing.

Another object of this invention is to provide a method of the character mentioned that may be easily and quickly carried out with a minimum number of simple operations.

Another object of this invention is to provide apparatus useful in excluding encroaching fluids from a well that comprises a frangible or friable

member that may be drilled from the well when the water bearing sand has been cemented off leaving the well bore entirely clear and unobstructed.

Another object of the invention is to provide apparatus useful in excluding fluid from a well that assures the proper placement and distribution of the sealing cement.

A further object of the invention is to provide an apparatus for use in excluding water or other fluid from a well that is very simple and inexpensive of manufacture.

The various objects and features of the invention will be fully understood from the following detailed description of a typical manner of carrying out the method and a typical form of the invention, throughout which description reference is made to the accompanying drawings, in which:

Fig. 1 is a longitudinal cross section of a portion 20 of a well bore illustrating an underreamer operating therein to provide an enlargement or cavity at the point of entrance of fluid to the well. Fig. 2 is a view similar to Fig. 1 illustrating the friable member and its baskets in position to receive the cement. Fig. 3 is a view similar to Fig. 2 showing the cement filling the member and expanding the baskets to occupy the enlargement or cavity and Fig. 4 is a view similar to Fig. 3 illustrating a drill drilling out the friable member and the excess cement in the well. 25 30 35

In the drawings the well bore B passes through or penetrates a stratum S that bears water or other undesired fluid which is entering or which has entered the well bore. The strata A above 35 and below the stratum S may be considered as shale, or the like, while the stratum B below the lower stratum A may be considered as a productive sand bearing oil or gas, or both.

It is believed that the method provided by the present invention will be better understood after reference has been made to the apparatus employed in performing or carrying out the method. Accordingly, we will proceed with a detailed description of a typical embodiment of the apparatus and will then describe the method as carried out in employing the apparatus.

The apparatus provided by the invention and employed in carrying out the method of the invention includes, generally, an underreamer 10 for enlarging the well bore B at the stratum S, a tubular string 11 adapted to be run into the well, a drillable or friable perforate member 12 detachably connected with the lower end of the string 11, a basket 13 on the member 12 to re- 50 55

ceive cement for filling the enlargement or cavity C made by the underreamer 10, and a drill D for drilling up the member 12 and the cement remaining therein and remaining in the well bore 5 proper following the setting of the cement.

The invention contemplates the employment of any desired form or type of underreamer for making the enlargement or cavity C in the well bore at the water bearing stratum S. It is preferred to employ an underreamer capable of making an enlargement or cavity C considerably larger in diameter than the well bore B. The particular underreamer 10 illustrated is intended merely to be illustrative of a typical tool of this 10 class and includes a body 14 carrying a plurality of cutters 15 mounted to expand or move outwardly. As shown in Fig. 1, the cutters 15 are in their expanded positions. The underreamer body 14 is attached to the lower end of a drilling 15 string or operating string 16 and the underreamer is operated by rotation of the string in the usual manner. Before running the underreamer 10 into the well it is preferred to definitely locate the stratum S bearing the water or encroaching fluid. This location of the stratum S 20 may be accomplished by any of the well known methods. It may be preferred to carry or extend the cavity C beyond the upper and lower limits of the stratum S, as illustrated throughout 25 the drawings. After forming the cavity C the cutters 15 are retracted and the underreamer is removed from the well bore on the operating string 16.

The string 11 is provided to run the friable 30 member 12 into the well and to conduct the cement to the member. In accordance with the invention the string 11 is tubular and may be made up of a plurality of lengths of pipe or tubing.

The member 12 is an important feature of the present invention. The member 12 is an elongate part proportioned to be received in the well bore B with suitable clearance. The friable member 12 is preferably sufficiently long to extend beyond the upper and lower limits of the cavity C when in its proper position or location in the well bore B. A longitudinal opening 17 enters the member 12 from its upper end and extends to a point adjacent the lower end of the 45 member. The lower end of the opening 17 is closed and a tapered or rounded nose 18 is provided on the lower end of the member to guide it in the well bore B. The upper end 19 of the member 12 is preferably tapered downwardly and 50 inwardly for the purpose to be hereinafter described. In accordance with the invention the member 12 is releasably connected with the lower end of the string 11 to have its opening 17 in communication with the opening of the string. In 55 practice the member 12 may be releasably connected with the string 11 in any suitable manner or by means of any suitable device; for instance, by a releasable adapter, a safety joint, or by left hand threads 20 as illustrated in the drawings. The threads 20 being left hand threads may be easily released or unthreaded without 60 loosening the usual right hand threads in the string 11. The invention provides a plurality of circumferentially and longitudinally spaced ports 65 21 in the wall of the member 12. It is a feature of the present invention that the member 12 is drillable or friable being formed of cement, Bakelite, hard and brittle rubber composition, glass, ceramic material, or any other material that 70 may be readily broken up or drilled up by drilling 75

tools. Owing to the fact that the member 12 is encased in cement when it is to be drilled up it may be desirable to form the member 12 of cement, it being understood that the member may be formed of any material that is readily drilled up, as just described.

In the preferred form of the invention illustrated means is provided for preventing a reverse or upflow of cement from the opening 17 to the string 11 and to prevent the loss of pressure on the cement in the opening 17 and the cavity C. I have shown a check valve arranged in the upper portion of the opening 17 to prevent the reverse flow of cement and the loss of pressure on the cement. The particular check valve illustrated includes a seat 22 arranged across the upper portion of the opening 17. The seat 22 is frangible or friable, being formed of cement, or the like, and is provided with a central opening 23. A ball 24 is provided to seal upwardly against the seat 22 to close its opening 23. The ball 24 may be formed of hard rubber or a suitable composition. A cage is provided to hold the ball 24 when in its open position. The cage may comprise wires 25 having their ends embedded in the seat 22 or the member 12. The ball 24 is adapted to seal upwardly against the seat 22 by internal pressure in the opening 17.

The basket 13 is provided to receive the cement as it discharges from the ports 21 and is operable to expand into the cavity C by the internal pressure of the cement to hold the body of cement in the cavity C and prevent its loss longitudinally in the well bore. The basket 13 includes a main skirt or main basket part 26 surrounding the member 13 and extending throughout the perforated portion of the member. The main basket part 26 is preferably formed of rubber to be expandable or if desired the part 26 may be formed of canvas, in which case it is initially pleated to be expandable. The lower end portion of the basket part 26 closely embraces the member 12 at a point below the lowermost ports 21. A band 27 or other means may be employed to hold the lower end portion of the basket part 26 in tight engagement with the external surface of the member 12 so that it is closed against the leakage of the cement. The main basket part 26 extends upwardly some distance beyond the uppermost ports 21.

The basket 13 includes an upper apron or skirt 28 which extends into the upper end of the main basket part 26. By this arrangement the basket 13 includes two overlapping or telescoping basket sections making it such as to readily expand and conform with the bore into which it is forced. The skirt 28 may be formed of rubber or canvas and is adapted to expand outwardly as the basket becomes filled with cement. It is preferred that the skirt 28 extend downwardly a considerable distance into the main basket part 26 to prevent the upward escape of cement from the interior of the basket. A band 29 or other means may secure the upper end of the skirt 28 to the member 12. A plurality of spaced openings 30 may be provided in the main basket part 26 to discharge a limited amount of cement into the stratum S in the event that the stratum S is porous to absorb the cement. The openings 30 are preferably spaced a considerable distance from the opposite ends of the basket to prevent the leakage of the cement into the well bore B.

The drill D is employed to drill up the friable member 12 and the cement remaining within the member 12 and surrounding the member in the

well bore proper following the cementing operation. The invention contemplates the employment of any suitable form of drill for drilling up the friable member 12 and the excess cement remaining in the well bore. It may be found desirable to employ a pilot bit or a diamond point bit of the type illustrated which is operable to first enter the projecting upper end of the member 12 and then cut away the member and the excess cement as it is fed downwardly. The diamond point drill D illustrated in the drawings is adapted to be run into the well bore on an operating string or drilling string 32. The drill D has a pointed lower end 33 having downwardly and inwardly inclined cutting edges 34. The drill D has the usual discharge ports 35 for the discharge of the circulation fluid during drilling. It may be preferred to employ a drill D having an effective diameter equal to the diameter of the well bore B so that it is operable to drill out all the cement in the well bore proper leaving the bore clear and unobstructed.

It is believed that the operation of the apparatus will be readily understood from the following detailed description of the method of the present invention as carried out with the apparatus. The method of this invention as practiced with the apparatus described above includes, generally, forming an enlargement or cavity C in the wall of the well bore B at the stratum S bearing the encroaching fluid, positioning a perforate friable member 12 and a cement basket 13 in the well bore B at the cavity C, passing or delivering cement 40 to the member 12 and the basket 13 to expand the basket and fill the cavity C, allowing the cement 40 to set, and then drilling out the friable member 12 and more or less of the cement in the well bore B to leave the desired size of bore and to leave a shell or lining 41 of cement in the cavity C to shut off the encroaching fluid from the well bore.

The forming of the enlargement or cavity C may be readily accomplished by the underreamer 10 or by an equivalent tool. The underreamer 10 is run into the well bore B on the string 16 to the previously located stratum S and the string is operated to expand the cutters 15 and is then rotated and fed downwardly so that the cutters 15 form the cavity C. It is preferred to extend the cavity C beyond the upper and lower limits of the stratum S so that the lining 41 of cement is anchored in the hard strata A. Following the forming or drilling of the cavity C the underreamer 10 is withdrawn from the well bore on the operating string 16.

Following the drilling of the enlargement or cavity C in the wall of the well bore B the friable perforate member 12 is run into the well on the string 11 to a position such as illustrated in Fig. 2 of the drawings. The member 12 is attached to the lower end of the string 11 by the left hand threads 20 or other suitable connecting means and the string 11 is run into the well in the usual manner to properly position the member 12 in the well bore where it extends through the cavity C to project beyond the upper and lower extremities of the cavity. After the member 12 has been positioned the invention provides for the delivering of cement to the member to expand its basket 13. The cement may be delivered or passed to the member 12 by means of any of the well known methods, for example, the cement may be delivered to the member 12 in a drop bottom brazier or by the Perkins method. It is preferred to pump the cement into the member 12 or put the

cement under pressure so that it flows through the ports 21 into the basket 13 under a suitable pressure. The cement readily passes the check valve 24 and then flows through the opening 17 to pass out through the ports 21 into the basket. 5

The cement under pressure entering the basket 13 expands the main basket part 26 and the skirt 28. The basket part 26 and the skirt 28 are expanded outwardly until they bear with pressure against and conform to the walls of the cavity C. 10 In the event that the stratum S is porous the cement passes out through the openings 30 into the stratum. A sufficient quantity of cement 40 is delivered to the member 12 to fully expand the basket 13 against the walls of the cavity C and 15 to flow into the stratum S until the stratum has absorbed sufficient cement. It is preferred to employ a quick setting cement so that the body of cement in the basket and encasing the member 12 will quickly harden or set. When the basket 20 13 has been properly expanded and the stratum S filled with cement until it no longer absorbs the cement, the pressure may be removed from the cement allowing the valve 24 to close against the seat 22. The cement that may remain in the string 11 is then removed as by bailing. The valve 24 closed against the seat 22 maintains the pressure on the body of cement 40 and prevents the upflow of the cement into the string 11. Following the cementing operation the string 11 is 30 released from the member 12 and withdrawn from the well bore. The cement 40 is then allowed to set or harden.

The final step of the method is the drilling up of part or all of the friable member 12 and the cement remaining in the well bore proper. This may be readily accomplished by any suitable form of drilling tool. It is preferred, however, to employ a rotary drilling tool so that the body of cement 40 is not shattered. In most instances it may be preferred to employ a pilot drill or a diamond point drill of the type illustrated. A pilot drill or the diamond point drill D first enters the opening 17 of the projecting upper portion of the member 12. The tapered upper end 19 of the member 12 guides the entering end 33 of the bit into the opening 17. As the bit or drill D is rotated and fed downwardly it drills away the friable member 12 and the cement 40 within the member and the portion of the body of cement immediately surrounding the member. When the drill D is of the same effective diameter as the adjacent portions of the well bore B it drills an opening 42 in the body of cement 40 of the same diameter as the well bore, leaving a lining or sleeve 41 of cement in the cavity C which fully shuts off the fluid in the stratum S. The drill D is capable of drilling out the entire member 12 and the excess cement 40 in the well bore forming an opening 42 of the same diameter as the well bore B. The basket part 26 and the skirt 28 in being formed of rubber or canvas are readily cut or drilled away by the drill D without endangering the cement sleeve 40 occupying the cavity C. After the drill D has drilled through the body of cement 40 and has fully drilled away the friable member 12 it is removed from the well bore on its operating string 32 leaving the well bore clear and unobstructed for further operations. The cement lining or sleeve 41 left in the cavity C 70 effectively shuts or seals off the undesired fluid of the stratum S from the well bore B.

The apparatus and method provided by the present invention is adapted to be employed for sealing leaking well casing. When employed for 75

this purpose the member 12 with its basket 13 may be substantially as described above and is positioned in the casing at the point of leakage. The inside wall of the casing at said point would 5 correspond to the bore at C, above described, except that it would not ordinarily be in the form of a cavity. Cement is then delivered or passed to the member 12 through the string 11 to expand the basket 13 and pass out through the openings 10 30. The cement leaving the openings 30 enters the crack or opening in the casing and possibly the opening behind the casing to seal the same. The cement is preferably pumped into the member 15 12 or put under pressure and when a proper quantity of the cement has discharged into the basket 13 the pressure is removed from the cement and the string 11 is detached from the member 12 and withdrawn from the well bore. The cement is then permitted to harden or set. 20 After the cement has set, the member 12 and the excess cement remaining within the casing is drilled up by means of a suitable drilling tool leaving the casing clear and unobstructed. The cement which will have entered the opening in 25 the casing effectively seals the casing against leakage.

Having described only a typical preferred form of the apparatus and a typical manner of carrying out the method of the invention, we do not 30 wish to be limited or restricted to the specific details set forth, but wish to reserve to ourselves any changes or variations that may appear to those skilled in the art or fall within the scope of the following claims:

- 33 Having described our invention, we claim:
1. Apparatus of the character described including, an integral drillable tubular member closed at its lower end and adapted to be run into a well, the member having a longitudinal opening and longitudinally spaced lateral ports, and 40 a tubular basket surrounding the member to receive cement from the ports.
  2. Apparatus useful in excluding encroaching fluid from a well including a drillable member 45 adapted to be run into the well on a string, the member having a longitudinal passage for conducting cement from the string and a plurality

of longitudinally spaced lateral ports communicating with the passage, a valve in the passage above the ports for preventing reverse flow of the cement, and a basket on the member for receiving cement from the ports and expansible by the cement to occupy a cavity in the well wall, the member being drillable to be drilled up after setting of the cement.

3. Apparatus useful in excluding encroaching fluid from a well including, an integral drillable 10 member adapted to be run into the well on a tubular string, the member having a longitudinal opening communicating with the string and a plurality of vertically spaced lateral discharge ports, and a basket on the body adapted to receive cement from said ports to be expanded thereby into a cavity in the well wall, the basket including telescoping oppositely extending expansible skirts surrounding the body, the member being drillable to be drilled up after setting of the 15 cement.

4. Apparatus useful in excluding encroaching fluid from a well including a drillable member adapted to be run into the well on a tubular string, the member having a longitudinal opening 25 for receiving cement under pressure from the string and longitudinally spaced ports for discharging the cement, and a basket on the member for receiving the cement from the ports and expansible into a cavity in the well wall by the 30 cement passed into it, there being openings in the basket to discharge cement into the earth formation, the member being drillable to be drilled up after setting of the cement.

5. A device of the character described comprising, a cast drillable member having a longitudinal opening entering its upper end and longitudinally spaced lateral discharge ports extending outwardly from said opening, the member having an integral wall closing the lower end of the opening, 40 an expansible basket on the member for receiving cement from the ports, and a valve at the upper end of the passage for preventing a return flow of fluid therethrough.
